UNITED STATES PATENT OFFICE.

ROY N. DONEY, OF AUBURN, NEW YORK.

AEROPLANE SPEED-BOAT.

1,333,799.

Specification of Letters Patent. Patented Mar. 16, 1920.

Application filed August 21, 1919. Serial No. 318,995.

To all whom it may concern:—

Be it known that I, ROY N. DONEY, a citizen of the United States, residing at Auburn, in the county of Cayuga and State of New York, have invented certain new and useful Improvements in Aeroplane Speed-Boats, of which the following is a specification.

This invention is an aeroplane speed boat which is constructed so that when momentum is gathered and the engine is running the weight of the boat will be suspended by planes connected thereto although the propeller and keel will be submerged in water, thus causing the resistance of the water acting on the revolving propeller to drive the boat more rapidly than if the propeller were operating in the air, while the keel will steady the movements of the boat in flight.

Another object of this invention is the production of an aeroplane speed boat which is so constructed that the planes will lift a boat body from the water and suspend the same as the device gathers speed, although the propeller will be submerged in water at all times, thus holding the boat hull free from action by rough water and in this way overcoming sea sickness.

A still further object of the invention is the production of an aeroplane speed boat which includes a false keel carried upon the hull of the boat this keel increasing in height toward its rear end, so that when the device is in use and the planes contiguous to the forward end of the hull lift the same, the keel at the rear portion will still be submerged so that the propeller will still operate within the water and thus from a minimum amount of power will attain the greatest result in speed due to the resistance of the water against this propeller and causing the same to be driven forwardly by the small resistance of the boat hull being suspended in air will allow the device to move rapidly.

One practical form of construction and assembly of the present invention will be hereinafter described and is illustrated in the drawing, in which—

Figure 1 is a side elevation, partly in fragmentary section of the complete device.

Fig. 2, is a top plan view of the device with one of the wings shown fragmentary.

Fig. 3, is a rear elevation of the device.

In the preferred embodiment of the pres-

ent invention, about to be specifically described, it will be understood that the principle of the invention is applicable to boat hulls of general type indicated at 5, having seats 5' or any other interior construction which does not in any way enter into the spirit of the present invention. It is well known that in the propulsion of such boats the resistance of the water against such movement is enormous. In high powered boats there is a considerable displacement of water at the bow of the boat which necessitates the employment of high power to overcome such resistance. In the use of aeroplanes, the resistance of air is very slight, but in such devices the propellers likewise are rotating against atmospheric pressure which does not allow of as great resistance against the propeller to increase the speed of the planes as can be accomplished by combined aeroplane speed boats. With such a device as will be apparent hereinafter, the planes will lift the forward portion of the boat from the water and thus overcome the resistance of water thereagainst, although the propelling means is submerged in the water and thus can propel the boat more rapidly in view of the increased resistance against such propeller which drives the same forwardly and as air pressure on the suspended boat body will resist such propulsion slightly, obviously the device can attain a higher rate of speed.

Stanchions 6 extend substantially vertically in pairs as shown in Fig. 1 adjacent each side of the hull 5 and support the planes 7 upon their upper ends, the outer ends of these planes being braced by guys 8 connected thereto and also connected to the stanchions 6 or to any other suitable support. These planes extend outwardly beyond each side of the hull as is obvious from an inspection of Figs. 2 and 3. Also the planes are carried contiguous to the forward end of the hull 5 so that as the speed is gathered and the air is banked beneath these planes the forward end of the hull will be lifted completely out of the water as will be hereinafter more apparent. It should be understood that although only monoplanes are illustrated herein, biplanes or any other greater number of planes desired may be employed, according to the necessity required by the size of the hull, without departing from the spirit of the present inven-

tion. It should be understood that the planes 7 extend on opposite sides of the hull 5 although the inner ends of the planes are spaced apart, thus allowing sufficient space 5 for the planes to be swung vertically upon suitable means or to not project beyond the sides of the hull when the device is entering a harbor on the surface of the water.

The keel 9 extends from the bow of the 10 hull 5 to the stern thereof, as is clear from an inspection of Fig. 1 and is somewhat similar to the ordinary manner of keels. However, with the present keel it will be seen that it tapers toward its front end as 15 shown at 10. Consequently it increases in breadth or height as at 11, at its rear end and for this reason at the stern of the hull it projects downwardly for a considerable distance therebelow. A high power engine 20 12 is provided and has its shaft 13 extending obliquely to the keel 11, the rear end of the keel being beveled off as at 14 to allow the propeller 15 to be carried upon the lower end of the shaft 13 to allow the propeller to revolve contiguous to the end 14 of the key 25 without interference from the keel. It should be understood however, that I reserve the widest latitude in respect to the connection from the engine to the propeller so that if 30 desired the propeller could be carried at the end of a shaft which extends horizontally so that the thrust of the propeller will be directly forwardly under such conditions, although it is not deemed necessary to illustrate such structure herein.

A rudder 16 is pivoted upon the rear end 35 of the hull 5 and has a handle 17 whereby the coxswain may easily steer the device. When in operation, the device will of course 40 rest upon the surface of a body of water. The engine may then be started and the hull will be driven forwardly in the usual manner. As the speed of the hull increases however, the planes 7 will bank air therebeneath and within a comparatively short 45 space will begin to lift the bow of the hull from the water. As this action starts the speed of the boat will increase, owing to the fact that resistance against the bow will be 50 decreasing. The boat will then proceed with ever increasing speed until the bow of the hull is entirely elevated from the water. Owing to the height of the keel 9 however at its rear end as at 11, the propeller will be submerged in the water and 55 as it rotates rapidly, being driven by a high powered engine 12, the resistance of the water against the rapidly rotating propeller will cause the hull to be moved forwardly 60 at an ever increasing speed until a maximum speed is attained. The hull will not be subjected to movement caused by rough water as it will be suspended by the planes 7 in the air and will in this way overcome 65 motion of water and will accordingly pre-

vent sea sickness from such movement. During such action the keel at its rear end will be submerged in the water and will thus steady the hull, preventing any tendency of side swinging of the hull. Thus 70 the hull will be held to its course so that wind will not vary or buffet the same, as is common with aeroplanes. As pointed out above, the propellers of aeroplanes being resisted only by atmospheric pressure have 75 not the resistance encountered by the propeller rotated in water. Consequently, the propeller in water has a greater resistance and for this reason because of rapid rotation will be driven forward very rapidly, 80 as it has great power due to this resistance of water. In an ordinary boat the propeller loses its power to a certain extent in view of the resistance of water at the bow of the boat. With the present device however with the bow and practically the entire hull suspended in air, the resistance of air against the hull will be very slight and thus the propulsive power of the propeller will 85 drive the hull very rapidly, since the portion of the keel which actually extends into the water will give so little resistance as 90 will make such resistance hardly appreciable.

It is obvious that in desired cases, the 95 size of the planes and the number thereof can be increased according to the proportion of the hull upon which the same are mounted, while the size of propellers or even the numbers of propellers may be increased upon the keels, according to the 100 size of a hull, and thus very large boats may be driven in a manner similar to the manner in which the invention now being 105 described is driven.

It will therefore be seen that a very simple and efficient means has been provided wherein the principles of an aeroplane and of a boat propelled by a high power engine are combined to unite the points of merit of 110 each and avoid the objections of each thus producing a device which will operate with maximum efficiency. It is obvious that while the boat is in operation it will not entirely slide through the air similar to an 115 aeroplane, but will tend to skim the surface of water to allow its propeller to be at all times submerged. When it is desired to enter a harbor, the speed of the engine may be decreased and consequently the hull will 120 drop back to the surface of the water and be propelled into the harbor in the manner usually employed in connection with ordinary boats.

The foregoing description and the drawings have reference to what may be considered the preferred, or approved form of 125 my invention. It is to be understood that I may make such changes in construction and arrangement and combination of parts, 130

materials, dimensions, et cetera, as may prove expedient and fall within the scope of the appended claims.

Having thus fully described my invention, what I claim as new and desire to secure by Letters Patent is:—

1. In a device of the class described, the combination of a hull, a lifting means contiguous to the forward portion of the hull, 10 a keel connected to the bottom of the hull and extending longitudinally thereof, said keel increasing in height toward its rear end, a propelling means carried by said hull and extending to the lower portion of 15 said keel as and for the purposes set forth.
2. In a device of the character described, the combination of a hull, planes carried

contiguous to the forward portions of the hull, said planes extending beyond opposite sides of the hull, the inner ends of the 20 planes being spaced apart thus allowing the space above the hull to be unobstructed, a keel carried upon the bottom of the hull and increasing in height toward its rear end, a propeller, and means for supporting 25 and driving said propeller at the lower portion of said keel, as and for the purposes set forth.

In testimony whereof I affix my signature in presence of two witnesses.

ROY N. DONEY.
